Primary Examiner — Darcey E Gottschalk

(57) **CLAIM**

The ornamental design for an expandable spinal fusion cage, as shown and described.

DESCRIPTION

1. Expandable spinal fusion cage

1.1 : Perspective

1.2 : Front

1.3 : Back

1.4 : Left

1.5 : Right

1.6 : Top

1.7 : Bottom

1.8 : Reference view of state of use

1.9 : Reference view of state of use

1.10 : Cross-sectional reference view showing the state of use taken in the direction of line A-A of Fig. 1.2

1.11 : Cross-sectional enlarged reference view showing the state of use taken from the broken line circle of Fig. 1.10
In the reproductions, the evenly-spaced broken lines show portions of an expandable spinal fusion cage that form no part of the claim; the dash-dot-dash lines represent boundaries of the claimed design that form no part thereof.

1 Claim, 11 Drawing Sheets(56)
